UNITED STATES PATENT OFFICE.

ROBERT A. WILSON, OF DALLAS, TEXAS, ASSIGNOR TO THE GUIBERSON CORPORATION, OF DALLAS, TEXAS, A CORPORATION OF DELAWARE.

WELL-TUBING CATCHER.

1,374,540.

Specification of Letters Patent. Patented Apr. 12, 1921.

Application filed February 20, 1920, Serial No. 360,031. Renewed February 24, 1921. Serial No. 447,551.

To all whom it may concern:

Be it known that I, ROBERT A. WILSON, a citizen of the United States, residing at Dallas, in the county of Dallas and State 5 of Texas, have invented certain new and useful Improvements in Well-Tubing Catchers, of which the following is a specification.

This invention relates to new and useful 10 improvements in well tubing catchers.

The invention has particularly but not necessarily to do with improvements upon the device covered by Letters Patent No. 1,218,549 issued to S. A. Guiberson, Jr., on 15 March 6, 1917. The improvement resides in providing an equal and positive bearing surface for the gripper slips or dogs in all their adjusted positions.

In the patented device the slips ride up 20 and down on a conical surface. The inner or bearing surface radius of each slip is constant while the radius of the conical surface varies from a maximum at the upper end to a minimum at the lower end. Consequently 25 the bearing surface of the slip if made to conform to the arch of the head at one location, would not fit and bear evenly on said surface when adjusted. By reason of this the strain must be sustained 30 to a large extent by the slips.

In carrying out the present invention the head is provided with inclined faces for the gripper slips, each face transversely curvilinear on a radius constant throughout its 35 length. Each slip has its inner face or surface transversely curvilinear on the same radius whereby it bears evenly on the inclined surface of the corresponding face on the head and contacts over its entire surface 40 at any of its adjustments. By such an arrangement an even distribution of the strain is had and is sustained by both the slip and the head substantially the same as if said head and slip were integral.

Other improved features will be herein-after more fully brought out.

The invention will be more readily understood from a reading of the following specification and by reference to the accompanying drawings in which an example of the invention is shown and wherein:

Figure 1 is a vertical sectional view of a well casing showing therein a tubing catcher 55 embodying my improvements,

Fig. 2 is an elevation of the head and tubing section, a portion of the head being in section and showing the collar and tubing cast therein.

Fig. 3 is an enlarged elevation of the head showing the face of one of the inclined bosses,

Fig. 4 is a cross-sectional view of the line 4-4 of Fig. 2, and

Fig. 5 is an underside view of the head. In the drawings the numeral 10 designates a well casing and 11 the section of the well tubing with which the catcher is embodied. 12 is an upper section of the tubing and 13 is a lower section of the same. These three sections sufficiently indicate the line of tubing which is of considerable length and weight.

The catcher includes a head 14 in which a collar 15 and the upper end of the tubing section 11 are cast. The lower end of the upper section 12 is screwed into the collar 15, and a collar 16 unites the lower end of the section 11 with the lower section 13. By casting the collar 15, section 11 and the head together, the parts are made integral and the head is thus better able to withstand the longitudinal thrust incident to the operation of the gripper slips.

I have shown three gripper slips or dogs 17 although the number may vary, and each has the usual teeth 18 on its outer face. The head is formed with a plurality of upwardly and outwardly inclined faces 19, one for each slip. At the base of each face a lug 20 is provided and each lug has its upper surface in the form of an inward and outward bevel 21. Each slip has its lower end 22 correspondingly beveled to fit the bevel 21. The slips are wedge-shaped and when inoperative rest on the lugs in which position their teeth 18 are within the diameter of the head and lugs and therefore cannot engage or catch on the casing. The beveled faces 21 and 22 tend to guide the slips inward as will be apparent.

The very important feature of the invention is the curvilinear surfaces or faces 23. Each face is curvilinear transversely on the same radius throughout its entire length and the inner face of each slip is correspondingly curved, thus the entire inner face of a slip will contact with its face on the head at any elevation to which it is adjusted.

The curvature of the faces is clearly illustrated in Fig. 4, where it will be seen that the center of the arch becomes eccentric and the radius is constant. The faces on the 5 head are formed in rectangular panels so that the slips have an equal bearing at all elevations. Converging sumps 24 are provided between the faces which also act as fluid courses. The advantage of this structure will be appreciated when the enormous strain and shock to which the slips 10 must be subjected is considered. Each slip contacting throughout its entire area will be sustained by the head which will absorb the 15 shock and will bear the strain. It will be seen that in structures where the slip does not contact along its sides with the head there is liability of the slip breaking or cracking under uneven strains.

20 A collar weight 25 is slidable on the section 11 below the head. Counter-sunk ears 26 in the upper edge of the collar weight receive the lower ends of links 27 which slide through enlarged slots 28 in the lugs 25. Each link has its upper end pivoted in the bottom of a slip. When the collar weight is displaced upward on the tubing section the slips 17 are moved upward by the links 27. The collar weight is partly supported on a coiled spring 29 surrounding the section 11 and resting on the collar 16. The spring is only partly compressed by the collar weight thereby preventing to a great extent the ordinary slight vibration of the 35 spring, occasioned by stopping and starting the tubing while lowering it into, and raising it out of the well, and the vibrations caused in pumping, which vibrations in ordinary practice are sometimes sufficient to 40 cause the slips to move upwardly and into contact with the casing.

If the tubing should break the inertia of the collar weight 25, accentuated by the tendency of the spring to expand will cause 45 said collar weight to maintain its position. The head and tubing section, however, being attached to the line of tubing will tend to descend more rapidly; consequently the links 27 being sustained by the inert collar 50 weight will support the slips 17 and the latter will be thrown outward by the inclined faces 23 when the head moves downward. The teeth 18 being sharp and hard will readily bite into the casing 10 and hold 55 against a further drop. It will be seen that the inner face of each slip 17 is at all times in contact with the faces 23 and the slips are thus firmly supported by the head. This makes a very substantial structure and reduces the liability of breaking, cracking and 60 chipping to a minimum.

The purpose of the beveled lugs and the lower ends of the slips being beveled to fit is to hold the slips into contact with the 65 faces of the head by means of the collar

weight only part of its weight being supported by the coil spring.

The invention is not limited to a tubing catcher as the transverse curvilinear faces with a constant radius and slips with inner 70 faces of the same radius could be used in other oil well and well drilling tools.

Various modifications may be made in the construction shown in the drawings and above particularly described, within the 75 purview of my invention.

What I claim is:

1. A well tubing catcher comprising, a head having longitudinally extending inclined portions, converging downwardly, 80 each portion having a face curved in cross section, said face being formed upon an arc having a constant radius throughout the entire length of the face, and gripping slips extending longitudinally of said portions, 85 said slips having inner inclined faces converging downwardly, each slip face being curved in cross section and formed upon an arc having a radius constant throughout the entire length of the slip, whereby the 90 slip face closely fits the face of said portion throughout its entire length and such close fitting is permanently maintained during the operation of the device.

2. A well tubing catcher comprising, a 95 head having longitudinally extending inclined portions converging downwardly, each portion having a face curved in cross section, said face being formed upon an arc having a constant radius throughout the 100 entire length of the face, gripping slips extending longitudinally of said portions, said slips having inner inclined faces converging downwardly, each slip face being curved in cross section and formed upon an arc having a radius constant throughout the entire length of the slip, whereby the slip face closely fits the face of said portion throughout its entire length and such close fitting is permanently maintained during the 105 operation of the device, and means to move the slips longitudinally with relation to such portions.

3. In a device of the character described, a tube section, a sleeve internally threaded 1 to receive the end of the tube section, a head cast upon the sleeve and upper end of the tube section to be rigidly connected therewith, said head having longitudinally extending inclined portions converging downwardly, 120 said portions being spaced to form longitudinal passages and each portion having a face curved in cross section, said face being formed upon an arc having a constant radius throughout the entire length of the 125 face, said head being provided at its lower end with lugs, said lugs having openings formed therethrough, links slideable within the openings, a collar weight slideable upon the tube section beneath the lugs and pivot- 130

ally connected with the links, a spring surrounding the tube section and engaging the collar weight, and gripping slips extending longitudinally of said portions, said slips having inner inclined faces converging downwardly, each slip face being curved in cross section and formed upon an arc having a radius constant throughout the entire length of the slip, whereby the slip

face closely fits the face of said portion, throughout its entire length and such close fitting is permanently maintained during the operation of the device, and an upper tube section engaging within the screw-threaded sleeve.

In testimony whereof I affix my signature. 15

ROBERT A. WILSON.
